(57) **CLAIM**

The ornamental design for a container rack, as shown and described.

DESCRIPTION

FIG. 1 is a front isometric view of a container rack according to a first exemplary embodiment;

FIG. 2 is a rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a bottom plan view thereof;

FIG. 8 is a top plan view thereof;

FIG. 9 is a cross-sectional view thereof taken along the lines 9-9 in FIG. 3;

FIG. 10 is a cross-sectional view thereof taken along the lines 10-10 in FIG. 3;

FIG. 11 is a cross-sectional view thereof taken along the lines 11-11 in FIG. 3; and

FIG. 12 is a cross-sectional view thereof taken along the lines 12-12 in FIG. 3.

FIG. 13 is a front isometric view of a container rack according to a second exemplary embodiment;

FIG. 14 is a rear isometric view thereof;

FIG. 15 is a front elevation view thereof;

FIG. 16 is a rear elevation view thereof;

FIG. 17 is a left side elevation view thereof;

FIG. 18 is a right side elevation view thereof;

FIG. 19 is a top plan view thereof;

FIG. 20 is a bottom plan view thereof;

FIG. 21 is a cross-sectional view thereof taken along the lines 21-21 in FIG. 15;

FIG. 22 is a cross-sectional view thereof taken along the lines 22-22 in FIG. 15;

FIG. 23 is a cross-sectional view thereof taken along the lines 23-23 in FIG. 15; and,

FIG. 24 is a cross-sectional view thereof taken along the lines 24-24 in FIG. 15.

The portions of the container rack shown in broken lines are for illustrative and environmental purposes and form no part of the claimed design.

(Continued)

Applicant reserves the opportunity to disclaim any (and all) solid line features including walls, cutouts, openings and projections during the examination phase.
